[57] CLAIM

The ornamental design for a container for storing multiple rolls of toilet paper, as shown and described.

DESCRIPTION

FIG. 1 is a perspective view of the container for storing multiple rolls of toilet paper showing my new design;
FIG. 2 is a front elevational view thereof, the rear elevational view, the left side elevational view and the right side elevational view being identical thereto;
FIG. 3 is a top plan view thereof; and,
FIG. 4 is a bottom plan view therof.

1 Claim, 2 Drawing SheetsFIG. 1.

FIG. 2.

FIG. 3.

FIG. 4.
